MINIATURE COMBINATION TUNING MEANS

George M. Gaskill and Manfred G. Wright, Kokomo, Ind., assignors to General Motors Corporation, Detroit, Mich., a corporation of Delaware

Application August 2, 1956, Serial No. 601,678

14 Claims. (Cl. 250—40)

This invention relates to means for tuning radio apparatus and more specifically to combination tuning means providing manual, mechanical preset specific station and automatic indexing of the apparatus operable upon the arrival of received signals. In early radio communication equipment the tuning of the apparatus over a predetermined frequency band was accomplished by some manual means for moving adjustable tuning apparatus. Later preset mechanical adjustable means was provided which was capable of moving the tuning means quickly to given locations to tune in a plurality of preset and most frequently listened to stations. At a still later date tuning equipment was provided for automatically scanning the frequency band for which the apparatus was designed together with automatic indexing means to stop the tuner upon the receipt of an incoming signal from any given station. This latter type of equipment has been identified as "signal seeking" tuning means or "stop-on-signal" apparatus.

It is an object in making this invention to provide means for tuning radio apparatus over its designed band which may selectively be operated manually, to preset mechanically locked positions, or automatically indexed upon the receipt of an incoming signal.

It is a further object in making this invention to provide radio tuning means which is a combination of manual, mechanical or signal seeking action, any one type of which may be operated immediately without the necessity of using any selecting or adjusting part to provide the desired type of operation.

It is a still further object in making this invention to provide combination tuning means having a minimum number of operating parts and of minimum size requirements to provide the desired action.

With these and other objects in view which will become apparent as the specification proceeds, our invention will be best understood by reference to the following specification and claims and the illustrations in the accompanying drawings, in which:

Fig. 1 is a front elevation of a radio receiver showing the dial and tuning means mounted therein;

Fig. 2 is a top plan view of the combination tuning means embodying our invention;

Fig. 3 is a side elevation taken from the left-hand side as shown in Fig. 2;

Fig. 4 is a bottom plan view of the tuner;

Fig. 5 is an enlarged side elevation taken from the right-hand side of Fig. 1, parts being broken away and shown in section, and taken on lines 5—5 of Fig. 6;

Fig. 6 is a sectional view from the top taken on lines 6—6 of Fig. 5, parts being broken away and shown in section;

Fig. 6A is a sectional view through the clutch driving portion taken on line 6A of Fig. 6;

Fig. 6B is an enlarged sectional view of the governor gear train load.

Fig. 7 is a sectional view showing the solenoid re-loading action taken on line 7—7 of Fig. 8;

2

Fig. 8 is a sectional view taken on line 8—8 of Fig. 5;

Fig. 9 is a circuit diagram of the control circuit for the loading solenoid;

Fig. 10 is a perspective view of the switch operating mechanism for controlling the loading solenoid;

Figs. 11, 12 and 13 are each a perspective detail view of one of the switch actuating levers that provide the compound control for the loading solenoid.

Referring now in particular to the drawings as shown therein in Fig. 1, the front panel 2 which may be the supporting panel in a vehicle and through which the various control means project and also through which the indicating means is visible. Panel 2, therefore, contains a rectangular opening 4 through which a series of push buttons 6 may project, the pressure on any one of which will bring the tuner quickly to a predetermined station. On one side a shaft bearing a control knob 8 projects through the panel and said control knob may operate the on-off switch and volume control. Located 10 on the other side of the panel is a second rotatable control knob 10 which is similarly mounted on a shaft to manually tune the receiver to desired stations. Between the two knobs 8 and 10 there is a second elongated opening 12 in which is mounted a transparent glass plate to 15 cover the same and behind which a dial 14 may be mounted. The dial is calibrated in terms of frequencies over which the receiver may be tuned and an indicating pointer 16 is provided to move across the dial to indicate the position of the tuning apparatus. Mounted above 20 the dial and projecting through an opening 18 in the panel 2 is a reciprocably movable bar 20 which operates a switch mechanism to control the signal seeking action of the tuner. Thus, if the operator desires to bring the tuner quickly to a preset station, pressure on any one of the push buttons 6 will quickly accomplish the result. If, on the other hand, the operator wishes to signal tune 25 the receiver, he momentarily depresses the push bar 20 to complete a control circuit to the signal seeking means which inaugurates seeking action automatically terminated upon receipt of a signal. Lastly, if he desires to manually tune the receiver to any desired location, he merely rotates the knob 10 to accomplish this end.

Referring now more particularly to Fig. 2, the tuning means is shown as including a main base 22 which extends from the left-hand side, as shown in Fig. 3, across to a point just beyond the last of the push buttons 6. This flat plate or base supports therebelow in normal position a plurality of slides and on its upper surface a plurality of means for tuning the receiver. The base 22 also has two side flange portions 24 and 26 that extend downwardly to form a housing below the plate for the mechanical slide section. A housing 27 is mounted on top of the base 22 by suitable cap screws 28. This housing supports tuning coils 30 whose inductances may 35 be changed to change the tuning of the specific radio circuit in which they are connected. Conventionally, these coils would be connected in the antenna, R. F. and oscillator circuits. In order to change the inductance of these coils so that the resonant circuits in which they 40 are connected may be tuned, there are provided a plurality of comminuted iron cores 36 which are commonly supported by a transverse bar 38 which is so mounted as to move reciprocably on the housing 27 and by so doing, move the cores 36 into and out of their respective coils to tune the apparatus. Each of the cores is connected to the transverse bar 38 by having a threaded member 37 cast in one end which threaded member is then threaded into an opening in the transverse bar 38 so that each may be adjusted linearly with respect to the 45 others for tracking purposes.

The transverse bar 38 has connected to opposite ends a plug 40 or 42 to carry the bar, which plugs extend

through slots 44 in the sides of the housing 27. The plugs 40 and 42 extend beyond the sides of the housing 27 and are each connected to the ends of pivotally mounted levers 46 and 48 by C-shaped coupling links 50 which are snapped over the ends of the plugs for application and which have their opposite ends pivotally connected to the levers as, for example, at 52 to the top of the angled lever 46 as best shown in Fig. 3. A bowed spring 51 clamped around the pivot 52 and extending under the head of plug 42 and bearing against the side of link 50 maintains the assembly in position and takes out lost motion. Link 50 on the right-hand side is similarly connected to the angled lever 48.

These two angled levers in combination with two transverse rods 54 and 56 form a pivotal assembly which may be designated as a treadle bar assembly. Rod 54 extends across between the two angled levers above the slide assemblies and rod 56 extends across in the same manner below the slide assemblies. The treadle bar assembly itself is pivoted about an axis midway between the two transverse rods. One end of this axis is determined by an opening 58 in the side wall 24 and a similarly located opening in the lever 46. A small ball bearing 60 is inserted between these two openings and held in place by end pressure when the treadle bar is snapped into position. On the other end a short stub shaft 62 is fixedly secured to the outside surface of angled lever 48. The axis of this stub shaft 62 coincides with the axis provided by the ball bearing 60. This stub shaft 62 projects through an opening in the side frame member 26 and extends through a hollow sleeve 64. Shaft 62 may rotate within the hollow sleeve 64.

Supported across the front of the assembly and secured to the two end plates 24 and 26 is a transverse member 66. This member has a plurality of openings therein and supports the various slide assemblies so that they may move reciprocably in the housing. A similar transverse supporting member 68 is secured across the back of the base to support the rear ends 70 of the slide assemblies. This type of tuner including an adjustable and lockable mechanical cam is shown in Schwarz et al. 2,489,544, issued November 29, 1949, entitled "Radio Tuning Means," and will not be described here in detail. Suffice it to say that each slide assembly is biased toward the front of the tuner by a coil spring 72 mounted between a shoulder on the slide and the end member 68 to bias the slide assembly forward. Each slide assembly includes an adjustable pivoted cam 74 which is held in locked position by a brake lever 76 as fully described in the Schwarz patent. This cam 74 is capable of engaging both of the transverse rods 54 and 56 in its reciprocal movement and first engages one, then further movement of the slide inwardly causes the treadle bar to turn until the other side of the cam 74 engages the other bar to index the same. This brings the tuner to a predetermined mechanical position, since the tuning means are mechanically linked to the upper end of the treadle bar assembly.

Pressure upon any of the mechanical push buttons 6 also operates clutch means to be described so that the tuner is substantially relieved of extra mechanical load during the mechanical preset cycles. This clutch operating means consists of a pivotally mounted transverse flanged bar 78 which extends across the whole housing and beyond into an area which supports both the manual and the signal seeking tuner portion of the apparatus. This flanged bar 78 may pivot about its longitudinal axis and is spring biased toward its uppermost position by a spring 80 one end of which is anchored to the frame side 24 and the other to a flanged tip 82 on the transverse bar 78. Extending downwardly from the flanged bar 78 at discreet intervals are a series of operating fingers 84 which are curved and extend into the proximity of operating plugs 86 on the rear face of each of the push buttons 6. Thus, when any of the push buttons are depressed, the plug 86 associated therewith presses against the curved

surface of one of the fingers 84 causing the flanged bar 78 to rotate about its axis. This motion will actuate clutch operating means to be described. Thus far the equipment described in detail is capable of quickly bringing the tuning apparatus to a predetermined mechanical setting upon the inward pressure on any one of the push buttons. The adjustable cam means 74 on any one slide may, of course, be reset to any other desired position by pulling outwardly on the associated push buttons 6 which unlocks the cam. Then by manually tuning the apparatus to a desired station the treadle bar will be moved to a given position associated with such station. When the push button is then pushed in all the way, the cam 74 will first be adjusted to a given position and then locked in that position. Thereafter, when that push button 6 is depressed, the new station will be tuned in as fully described in Schwarz et al. 2,489,544.

It has been mentioned that initial depression of any one of the mechanical push buttons 6 causes rotation of the transverse bar assembly 78 which was described as by a clutch operating means. The sleeve 64 on stub shaft 62 is capable of moving axially on said shaft. The sleeve is spring-biased to the right as shown in Figure 4 by a coil spring 90 which encircles the shaft 62 and bears against a disc 94 which in turn presses against the side frame member 26. The opposite end of the spring 90 engages the end of the sleeve 64 to force it toward the right. An integral enlarged ring 96 is supported on the inner end of the sleeve 64 to act as a shoulder for the clutch operating means forcing the sleeve to the left against the bias of spring 90. A clutch operating lever 98 has one end hooked through an opening in a flanged bracket 100 extending from the side of the frame member 26. The lever 98 has a central opening therein through which the sleeve 64 projects and each side part of the lever on opposite sides of the sleeve 64 has raised projections 102 which engage the side of the enlarged integral ring 96. Thus, when the innermost end of the lever 98 is forced to the left as shown in Fig. 4, these projections 102 press against the side of the ring 96 forcing the sleeve 64 to the left and compressing spring 90. This disengages the clutch means to be described.

Lever 98 is moved about its pivot in bracket 100 through engagement with a curved flanged arm 104 on the rotatable transverse bar 78 which engages a roller 106 on the innermost end of the pivoted arm 98. As the bar 78 rotates about its axis against the bias of spring 80 this curved flange 104 forces the end of the lever 98 to the left as viewed in Fig. 4. Mounted on the outside of sleeve 64 but rigidly connected thereto is a gear 108. Mounted adjacent to gear 108 and free on sleeve 64 is a second gear 110 connected to rotate with the first gear by springs 112 in order to absorb gear back-lash, thus rotation of the gear assembly 108—110 will drive the sleeve 64. Mounted on the right-hand end of the sleeve 64 is a first clutch plate 114. This clutch plate is adapted to engage a second spaced clutch plate 116 rigidly secured to the end of shaft 62 and which is rotatably supported on a ball bearing 118 sunk in the cupped end of a stub shaft 120 threaded through the frame wall. A layer of friction material 122 is provided between the clutch faces and secured to either one to provide for friction driving.

The manual drive and the signal seeking drive for the tuner are both provided through the gear 108 which drives sleeve 64 and clutch plate 114 then through clutch plate 116 to drive the shaft 62. A manually operable knob 124 is secured on the end of a rotatable shaft 126 which projects from the front of the tuner. This shaft has mounted thereon two externally threaded sections 128 and 130 which are secured together and rotate with but may move as a unit along the shaft 126. Section 128 has a spiral worm thread 129 which meshes with the gear wheel 108—110 mounted on the sleeve 64 and thus rotation of the knob 124 drives the sleeve 64 to turn the shaft 62 through engagement of the

clutch. The second section 130 is formed with circular threads 131 having no pitch which acts as a rack during longitudinal movement of the assembly 128—130 but does not prevent rotation of the assembly and shaft at any time. The shaft 126 extends through a central bore 132 in the section 128 and through a similar bore 133 in section 130. This latter bore is further provided with longitudinal slots 136 diametrically opposite each other to provide a keying support. A pair of tapered rings 138 and 140 are pressed on the shaft 126 and act as a ball support for ball bearings 142 located in each slot 136. One of the rings 138 has teeth 144 which keep the ball bearings from rolling around the rings and causes them to rotate with the shaft. Thus, the assembly of sections 128 and 130 rotate with the shaft 126 but may move longitudinally thereof on the ball bearings in slots 136 for purposes to be described. A press fit plug 146 closes the open end of section 130 to prevent dirt accumulating on the bearings.

Longitudinal movement of the assembly of sections 128—130 is caused by the power spring for driving the tuner for signal seeking indexing and such longitudinal movement forms part of the load on the spring and couples the spring drive to the gear train load and mechanically indexed wheel. This gear train load is best shown in Figure 6 and includes a housing 148 secured to a wall 150 of the frame. A first shaft 152 is rotatably supported in said housing. An elongated pinion 154 is secured on said shaft which pinion has an enlarged cupped end 156 having internal teeth 158. Also loosely mounted on shaft 152 is a spur gear 160 upon one side of which is secured a spring ratchet 162 having resilient arms engageable with the teeth 158 and providing one-way drive between the pinion 154 and gear 160. A second shaft 164 is likewise rotatably mounted in the frame and carries transfer pinion 166 and gear 168 rigidly secured together and rotating as a unit. A final shaft 170 is mounted in the housing parallel to the other two shafts and projects through an opening 172 in an inwardly projecting panel 174 on the housing. One end of the shaft 170 is toothed as at 176 to provide an elongated pinion which meshes with gear 168 and the other end of the shaft 170 has a cylindrical governor member 178 forced thereon to rotate with said shaft. The outer surface of the governor member is toothed at 180 for index purposes to be described.

The governor includes an axially movable plate 182 mounted on the shaft 170 which is biased toward the governor member 178 by a coiled spring 184 bearing against the plate 182 and a fixed washer 186. The plate 182 is designed to be forced against the spring 184 by ball bearings 188 which are retained in tapered grooves 190 in the side of the governor member 178 and are forced outwardly by centrifugal force. When the plate is forced against the bias of the spring 184 it engages a friction surface 192 supported on the side of panel 174 adjacent opening 172 to increase the load and tend to slow down the drive by conventional governor action. Thus, as the assembly 128—130 is driven axially toward the front of the frame by means to be described, the pinion 154 will be driven by the rack 129 of section 130. The pinion will in turn drive the gear 160 through the ratchet 162 and thence through pinion 166, gear 168 and pinion 176 to the governor 178 which controls the speed.

Mounted on the frame adjacent to the governor housing 148 and as best shown in Figures 5 and 6 is an indexing control relay 194 which is adapted to be energized during tuning periods and deenergized during listening periods of the apparatus by control circuits such as those previously mentioned. This control relay actuates a pivoted armature 196 whose end 198 projects out over the governor housing 148 and through an aperture 200 in said housing to engage the teeth 180 on the governor wheel 178 to index the same (see Fig.

5). When the relay 194 is energized, the end 198 will be moved out of engagement with the teeth 180 and the gear train may turn but when a signal is tuned in, the relay becomes deenergized and the detent drops in to stop the gear train and lock it.

The means for driving the tuner and the assembly 128—130 axially to scan the frequency band of the receiver will now be described. This consists of a power spring 202, one end of which is anchored to the frame at 204 and the opposite end of which is secured to a projecting tang 206 on arm 208 pivotally mounted on shaft 210. Shaft 210 has one end supported in a bracket 212 and at the other in a side frame member 215. As shown in Figure 7, the spring 202 tends to bias the arm 208 for clockwise rotation about shaft 210. The arm 208 (see Figure 13) has an integral plug 214 formed near its outer end which extends axially. An angled actuator lever 216 is also mounted across the end of the arm for purposes to be described (see Fig. 7). The plug 214 is adapted to fit in an annular groove 218 in the worm section 128, as best shown in Fig. 6. Thus, the section 128 may rotate freely about its own axis and plugs 214 will simply ride in the groove, but when the arm 208 is rotated about its pivot on shaft 210 either by the spring 202 or the cocking solenoid, the assembly 128—130 will be moved axially.

Cocking means for loading the spring 202 includes a solenoid coil 220 and its associated movable core 222, best shown in Figure 7. An irregularly shaped link 224 is pivotally connected to the core 222. From its pivotal connection to the core the link 224 extends down under the sleeve 64 and then laterally toward the front of the tuner. The forward section includes a slot 226 through which a pin 227 extends, which latter is carried on the end of a second shorter arm 228 pivotally mounted on the shaft 210. This provides a lost motion connection between the link 224 and the arm 228 (see Figure 12). The arm 228 is a switching and actuating arm and actuates switching means to be described. Arm 228 is an integral part of a longer lever arm 230, also pivotally mounted on shaft 210 in spaced relation, the two arms being connected together by a cross plate 213 (see Fig. 4) and leaving a cavity between the two in which arm 208 is mounted and nests, but out of which it is capable of moving to the left is shown in Fig. 7. A further cross plate 225 extends between the two arms 228 and 230 above the shaft 210. A biasing spring 232 has one end anchored to the frame at 234 and at the opposite end secured to an upstanding ear 236 on the link 224 to bias the link to the right as shown in Fig. 7.

There are two functions that are performed by the solenoid 220. The first is reloading or recocking the main driving spring 202 and the means for accomplishing this have just been described. The second function is to move the tuning means to one extreme position of its travel if it has reached the opposite limit of travel. As previously described, the type of signal seeking tuning means illustrated here is that in which the tuner is driven in one direction across the band at a suitable rate for indexing or seeking purposes. If a station transmitting a signal of sufficient strength is tuned in during this phase, the control relay 194 is deenergized and the mechanism locked on station. When the tuner reaches one end of its travel, however, it is necessary to quickly move it to its opposite extremity so that automatic scanning may again proceed. Therefore, the solenoid 220 must also be capable of quickly moving the tuning means to the low frequency end of the band. To provide this drive a third pivotally mounted arm 238 (see Figure 11) is mounted on shaft 210 and is connected to the clutch plate 116 by link coupling 134 (see Fig. 5). Thus, when lever arm 238 is rotated, the clutch plate 116 will likewise be rotated and shaft 62 directly connected thereto and to the treadle bar will be turned to move the tuning means.

In order not to overload the solenoid or to require an inordinately large solenoid, the apparatus is so arranged that only one of these parts at a time will be moved and that they will be moved in sequence. When the apparatus has moved to a point where the driving spring 202 has become discharged and should be recocked, suitable switching means will be closed to energize the solenoid 220 and it will draw in its armature 222 to rotate arm 208 and reload spring 202. This movement, however, does not move arm 238 to move the tuner to the low frequency end of the band. The solenoid is deenergized and spring 232 returns the slide link 224 to the withdrawn position. If at this time the tuner requires movement to the other end of the band, the solenoid will again be energized to draw in its core 222 and this time the arm 238 will be coupled to the link 224 and the tuner will be moved. However, since the automatic drive spring has already been cocked, its load will not be applied and only the force necessary to move the tuner is required. The system, therefore, applies two strokes, one to load spring 202 and the second to move the tuner if necessary. If the tuner is at some position other than at the high frequency end, the coupling will not be made and the solenoid will not be energized. Initial movement of the slide away from its position of rest actuates the clutch operating bar 78 through engagement of flanged operator 133 extending from the side of slide 224 which engages a curved foot 135 of the rotatable bar 78. Thus, the clutch is open whenever the slide moves.

This action may be generally explained by reference to the simple circuit diagram shown in Figure 9. In that instance a source of power 240 is shown connected to the solenoid coil 220 and also to ground. The solenoid coil is in turn connected through a normally closed switch 242 and thence through two parallel connected switches 244 and 246 to ground. The switches 242, 244 and 246 are mounted on the frame adjacent the various pivoted lever arms 208, 228, 230 and 238 (see Fig. 8) and are adapted to be operated by the movement of the link slide 224 and pivoted levers 238 and 208. The switch 242, as previously mentioned, is normally closed, and is only opened when the solenoid fully retracts its core within the coil to load whatever apparatus is operatively connected thereto. On the other hand, switches 244 and 246 are normally open switches, which are closed when either the driving spring 202 becomes discharged and needs recocking or the tuner assembly reaches the high frequency end of the band and must be moved to the low frequency end respectively.

Assuming for the moment that the spring 202 becomes unloaded and has moved the assembly 128-130 as far as it can to drive the tuner, then the adjustable limit screw 248 engages the switch operating arm 250 for the switch 246, which is mounted on an insulating panel 253 on the wall of the frame to close the same. Since the switch 242 is already closed, an obvious energizing circuit through switches 242 and 244 in series is completed for the coil 220 and it draws its core 222 inwardly, pulling the arm 228 toward it as shown in Figure 7. Arm 228 is integrally connected to arm 230 across behind pivoted lever 208 so that such movement of arm 228 not only moves integral arm 230 counterclockwise about shaft 210 as viewed in Figure 7, but at the same time carries with it arm 208, since that is nested between the two parts although physically unconnected. As soon as core 222 has been withdrawn completely within the solenoid 220, the position of the link 224 opens switch 242 by movement of ear 255 to deenergize the solenoid, and link 224 may be withdrawn toward the right as shown in Figure 7 by spring 232. Arm 208 will be retained in its extreme left position since plug 214 rests in annular slot 218 of the assembly 128-130 which has moved to the fully cocked position. One-way ratchet drive 162-158 permits this movement but the gear train is locked for return movement under control of detent 198.

The unitary assembly of arms 228 and 230, however, will be drawn back clockwise about shaft 210.

If at the time arms 228 and 230 are moved back, switch 246 is closed, indicating the necessity to move the tuning means to the low frequency end, then as soon as switch 242 assumes its normally closed position, a second circuit will be completed for the solenoid coil 220 and that will be again energized. On its second stroke, however, no motion will be imparted to arm 208 since that has already assumed its fully cocked position, but on this stroke the plate 238 will be picked up and drawn in a counterclockwise direction around 210 as seen in Figure 7, which movement will turn clutch disc 116 through link 134 to move the tuner to the low frequency end of the band, and thus reset the tuner. The means for causing this second stroke and a setting of the tuner are best shown in Figure 7 and consist of a pivoted toothed pawl 252 mounted on the top corner of arm 230. This pawl is spring biased downwardly by a biasing spring 254, one end of which engages the arm 230 and the other the pawl 252. This end of the arm 230 oscillates under a flange 256 on the upper edge of pivoted arm 238. In general, the flange is solid, but it contains an opening 258 best shown in Figure 6, into which the tooth 260 of the toothed pawl 252 may project to lock the lever arms 230 and 238 together for unitary motion under certain circumstances. The locked position of the tooth 260 is shown in dash and dotted outline in Figure 7.

Assuming that the solenoid has completed its first stroke and moved the arm 208 to its completely cocked position, which is shown in dash and dotted outline in Figure 7, upon a return of the linkage 224 to its remote right-hand position under the influence of spring 232, the arm 230 is moved back to its original position. As it moves, a second tooth 262 on the bottom of pawl 252 rides up on the cam spring 216 to force the pawl 252 clockwise about its pivot. When the pawl reaches a point adjacent the opening 258 in the flange 256, it projects through this opening and is held there by the end of the cam spring 216. Upon completion of the second circuit through switch 246, the solenoid 220 is again energized and link 224 is drawn to the left, as shown in Figure 7. This movement of arms 228-230 now picks up arm 238 and through the linkage 134 moves the tuning means to the low frequency end. Again, switch 242 opens as soon as the core 222 is drawn into the solenoid and the solenoid circuit is broken. Upon the second return stroke, however, both switches 244 and 246 are open and the cocking solenoid remains at rest until such time as either switch 244 is closed by the position of arm 208 or switch 246 is closed by the position of arm 238. The switches 244 and 246 are both mounted on the insulating block 253 on the inside of the frame and are thrown by adjustable limit screws such as 248 and 251 shown in Figure 5. The actuating arm 253 for these switches is, of course, of insulating material.

If the tuner reaches the high frequency end of its travel and the driving spring 202 has not completed its circuit through switch 244 to call for solenoid energization, the closure of switch 246 itself will complete a circuit for energizing the solenoid 220. This energization will again first pick up pivoted arm 208 to reload the driving spring 202 regardless of its intermediate position and move it to a completely loaded state. The solenoid will then become deenergized by the opening of switch 242 which is mechanically operated and the linkage 224 will return to its right-hand position to again close it. However, movement of the arm 208 has not opened switch 246 which still remains closed and the operation for moving arm 238 to move the tuning means per se will be repeated. Thus, if the driving spring becomes unloaded to close its switch 244 only, a single stroke of the solenoid will suffice, but if both switches are closed or switch 246 only, the solenoid will take two strokes to first load the spring

202 and then move the tuning means to its low frequency end of travel.

Referring now specifically to Figure 3, a momentarily closed energizing switch 270 is mounted on top of the frame of the tuner and provided with a manually engageable operating bar member 20. This switch is connected electrically in series with the control relay 194 as shown in the patent above referred to circuitwise so that the relay is energized when this switch is closed to inaugurate a signal seeking tuning cycle. When the operator depresses button 20 and relay 194 becomes energized, it lifts detent 198 out of engagement with the teeth 180 of the gear train load and governor. The spring 202 then turns the lever 208 about the shaft 210 and in so doing the plug 214 on said lever moves the threaded drive assembly 128—130 toward the front of the tuner. This motion, through the rack 130, drives the gear train with its associated governor at a regulated speed. At the same time the forward threaded portion 128 engages the gear 108—110 to drive the same as a rack. Rotation of gear 108—110 drives the clutch member 114, and through the clutch, the tuning means. When the tuner tunes in a station, the control relay 194 is deenergized and it drops detent 198 into engagement with the governor teeth 180 to immediately lock the threaded means 128—130 against further movement and index the tuner on station. When the threaded assembly 128—130 is moved quickly in the opposite direction to load the spring 202, the one-way drive clutch in the gear train at 162, 158 permits the major portion of the gear train to remain stationary while the threaded assembly is moved to its cocked position.

If the operator desires at any time to utilize the preset push buttons 6, he merely depresses the one desired. The first inward movement of the push button causes the clutch operating transverse shaft 78 to be rotated, which in turn pivotally moves the operating lever 98 to compress spring 90 and open the clutch, immediately disconnecting both the manual and the signal seeking portion from the tuning means. Further action of the slide brings a preset adjustable mechanical cam 74 into engagement with the opposite treadle bar arms 54 and 56 to index the tuner. Lastly, if the operator desires to manually move the tuner to any position, he may do so merely by rotating the knob 124. This knob drives the shaft 126 upon which the threaded assembly 128—130 is mounted to rotate that assembly. However, since the rear threaded portion 130 has threads of no pitch, the threaded assembly may rotate without tending to move the pinion 154 of the gear train, which is locked by detent 198. At the same time this rotation causes the worm portion 128 to drive the gear 108—110 and through the clutch to move the tuner to any desired position. With this design, therefore, manual, preset mechanical, or signal seeking tuning action is obtainable, and the device is simplified in that only a single small solenoid is utilized to either reload the power source for signal tuning or move the tuning means to one limit of its motion.

We claim:

1. In radio receiving apparatus, movable means for tuning the apparatus over a predetermined band of frequencies, a first driving means directly connected to said movable means, a plurality of presettable adjustable means individually operatively engageable with said first driving means to move the driving means to certain desired positions, a second driving means, clutch means interconnecting said first and second driving means, manually movable and power operated means connected to the second driving means to move the same and energizable means selectively connectable to the power operated means and to the movable means for tuning to sequentially charge the power operated means and move the movable means to one end of its travel.

2. In radio receiving apparatus, movable means for tuning the apparatus over a predetermined band of fre-

quencies; a first driving means directly connected to said movable means, a plurality of presettable adjustable means individually operatively engageable with said first driving means to move the driving means to certain desired positions, a second driving means, clutch means interconnecting said first and second driving means, power storage means connected to the second driving means to move the same and a single energizable means selectively operatively connected to said power storage means and said movable means to sequentially charge the power storage means and move the movable means to one extremity of travel.

3. In radio receiving apparatus, movable means for tuning the apparatus over a predetermined band of frequencies, a first driving means directly connected to said movable means, a plurality of presettable adjustable means individually operatively engageable with said first driving means to move the driving means to certain desired positions, a second driving means, clutch means interconnecting said first and second driving means, power storage means connected to the second driving means to move the same, a single energizable means selectively operatively connected to said power storage means and said movable means to sequentially charge the power storage means and move the movable means to one extremity of travel, and switching means controlled by the positions of the power storage means, the movable means and the energizable means and connected to the latter to control the energization thereof.

4. In radio receiving apparatus, movable tuning means for tuning the apparatus over a band of frequencies, a first driving means connected to said movable tuning means, a second driving means, clutch means interconnecting said first and second driving means, power storage means connected to said second driving means to move the same, and energizable means selectively connected to the movable tuning means and the power storage means to sequentially move the same.

5. In radio receiving apparatus, movable tuning means for tuning the apparatus over a band of frequencies, a first driving means connected to said movable tuning means, a second driving means, clutch means interconnecting said first and second driving means, power storage means connected to said second driving means to move the same, energizable means selectively connected to the movable tuning means and the power storage means to sequentially move the same, and a plurality of switching means connected in circuit with the energizable means to control the same, said switching means being actuated by the positions of the power storage means, the movable tuning means and the energizable means.

6. In radio receiving apparatus, movable means for tuning said apparatus over a predetermined band of frequencies, driving means connected to said movable means to move the same, a plurality of reciprocable members operably engageable with said driving means to move the same, power driven reciprocable means connected to said driving means, energizable means connected to said power driven reciprocable means and said movable means for tuning the receiver and control switching means connected to the energizable means to periodically energize the energizable means to alternately move the power driven reciprocable means and the movable means for tuning the apparatus.

7. In radio receiving apparatus, movable means for tuning said apparatus over a predetermined band of frequencies, driving means connected to said movable means to move the same, a plurality of reciprocable members operably engageable with said driving means to move the same, a second driving means, clutch means connecting said first and second driving means, reciprocable power driven means connected to said second driving means, and energizable means connected to said reciprocable power driven means and said first driving means

to move each sequentially to one extreme position of travel.

8. In radio receiving apparatus, movable means for tuning said apparatus over a predetermined band of frequencies, driving means connected to said movable means to move the same, a plurality of reciprocable members operably engageable with said driving means to move the same, a second driving means, clutch means connecting said first and second driving means, reciprocable power driven means connected to said second driving means, energizable means connected to said reciprocable power driven means and said first driving means to move each sequentially to one extreme position of travel, and a plurality of switching means operable by the positions of the movable means for tuning the apparatus, the reciprocable power driven means and the energizable means respectively, said switching means being connected to the energizable means and controlling its operable cycles.

9. In radio receiving apparatus, movable tuning means for tuning the apparatus over a predetermined band of frequencies, power storage means, clutch means interconnecting said power storage means and the movable tuning means, energizable means connected to both the power storage means and to the movable tuning means to independently move the same to one extremity of travel, interrelated switching means connected to the power storage means, the movable tuning means and the energizable means and operated by the positions of these parts, said switching means being connected in circuit with the energizable means to control the same.

10. In radio receiving apparatus, movable tuning means for tuning the apparatus over a predetermined band of frequencies, a first rotatable means connected to the movable tuning means to move the same, a second rotatable means, clutch means interconnecting the first and second rotatable means, gear means mounted on said second rotatable means, rotatable and reciprocable threaded means engaging said gear means and driving the same through either rotation or reciprocation of the threaded means.

11. In radio receiving apparatus, movable tuning means for tuning the apparatus over a predetermined band of frequencies, a first rotatable means connected to the movable tuning means to move the same, a second rotatable means, clutch means interconnecting the first and second rotatable means, gear means mounted on said second rotatable means, rotatable and reciprocable threaded means engaging said gear means and driving the same through either rotation or reciprocation of the threaded means, power means connected to the rotatable and reciprocable threaded means to drive the same and speed limiting means connected to the rotatable and reciprocable threaded means to govern the speed of movement.

12. In power apparatus, a solenoid, a core for said solenoid, a driving link connected to said core and reciprocated by movement of said core, a multi arm pivoted lever connected to the driving link through a lost-motion connection, a plurality of pivoted arms engageable by said first lever and movable by rotation of the lever, one of said plurality of arms being operatively connected to a first load and the other arm operatively connected to a second load and disengageable means carried by the multi arm lever to engage one of the arms and cause it to move so that the solenoid may cause movement of either of the plurality of arms selectively.

13. In radio apparatus, movable tuning means for tuning the apparatus over a band of frequencies, a first driving means connected to said movable tuning means, a second driving means, clutch means interconnecting said first and second driving means, power storage means connected to said second driving means to move the same, energizable means, reciprocable means connected to the energizable means and moved thereby, a multi arm pivoted lever connected to the reciprocable means, a plurality of pivoted arms engageable by said first pivoted lever and movable thereby, one of said arms being connected to the first driving means and the other arm being connected to the power storage means so that movement of the reciprocable means will move the arms to move the first driving means and the power storage means.

14. In radio apparatus, movable tuning means for tuning the apparatus over a band of frequencies, a first driving means connected to said movable tuning means, a second driving means, clutch means interconnecting said first and second driving means, power storage means connected to said second driving means to move the same, energizable means, reciprocable means connected to the energizable means and moved thereby a multi arm pivoted lever connected to the reciprocable means, a plurality of pivoted arms engageable by said first pivoted lever and movable thereby, one of said arms being connected to the first driving means and the other arm being connected to the power storage means so that movement of the reciprocable means will move the arms to move the first driving means and the power storage means, and selective coupling means between said one arm and the first pivoted lever so that said one arm is moved only under certain conditions.
